ERNST KOBEL, OF ENNETBADEN, SWITZERLAND, ASSIGNEE TO AKTIENGESELLSCHAFT BROWN, BOVERI & CIE., OF BADEN, SWITZERLAND, A JOINT-STOCK COMPANY OF SWITZERLAND

ELECTRIC CURRENT RECTIFIER CONTROL SYSTEM

Application filed August 15, 1930, Serial No. 475,503, and in Germany August 15, 1929.

This invention relates to improvements in electric current rectifying systems of the type utilizing the valve action of an arc flowing through a metallic vapor and particularly to a system for controlling the ignition or attachment of the arc to the anodes of the rectifier.

It is desirable and frequently absolutely necessary to vary the moment at which the arc is transferred from one anode to another in an electric current rectifier of the metallic vapor type with relation to the alternating current voltage wave. Grids, on which a voltage may be impressed, located adjacent the anodes, are commonly used for this purpose and it has already been proposed to displace the voltage phases of the anodes and their grids relative to each other to permit control of the anode current by the voltage impressed on the grids. Phase shifters and special voltage transformers were however required to attain the desired results which made the control system very complicated and expensive.

It is, therefore, among the objects of the present invention to provide a control system for electric current rectifiers of the metallic vapor type in which the moment of attachment of the arc to the anodes of the rectifier are positively controllable.

Another object of the invention is to provide a control system for electric current rectifiers in which grids are arranged adjacent the anodes of the rectifier and are connected with and controlled from discharge tubes for the purpose of controlling the attachment of the arc to the anodes.

Another object of the invention is to provide a control system for electric current rectifiers in which discharge tubes are connected with the anodes of the rectifier and are supplied with a voltage in addition to that of the anodes to control the potential of the grids connected with the tube and thereby control the attachment of the arc to the anodes.

Objects and advantages, other than those above set forth, will be apparent from the following description when read in connection with the accompanying drawing in which

Figure 1 diagrammatically illustrates one embodiment of the present invention showing the use of alternating current as the source for the additional grid control voltage, and

Figure 2 is a modification of the invention showing the use of a direct current source for the additional grid control voltage.

Referring more particularly to the drawing by characters of reference, the reference numeral 3 designates an alternating current supply line connected with the primary winding 4 of a transformer, the secondary winding of which is shown at 5. The several portions of the star-connected secondary winding 5 are each connected with and supply an alternating voltage to anodes 7 enclosed within a tank 8 also containing a cathode 9 of suitable vaporizable material having a valve action on electric current flowing through the vapor thereof. The electric current rectified during its passage from the anodes 7 to the cathode 9 is supplied to a work or current consuming circuit comprising a conductor 11 connected with the cathode and with a current consuming device 12 and a conductor 13 connected between the neutral point of the secondary winding 5 and the current consumer 12.

The circuit for controlling the flow of current from the anodes 7 is formed, as shown in Fig. 1, by grids 16 each of which are arranged within the tank 8 adjacent each of the anodes 7 and are adjustably connected through a resistance 17 with the secondary winding 18 of an auxiliary transformer. One end of the secondary winding 18 is connected with one of the electrodes of a discharge tube 19 and the other electrode thereof is connected with the portion of the supply transformer secondary 5 supplying voltage to the anode 7 under consideration. The primary winding 20 of the auxiliary transformer is connected across the supply line 3 as is customary. It will be understood that only the control system for one anode has been shown and that the system is to be duplicated for each anode to be controlled.

The modification as shown in Fig. 2 differs from that shown in Fig. 1 and above described only in the substitution of a source of

direct current 22 for the transformer 18, 20 without in any way varying the remaining portions of the system or materially altering the principle of its operation.

- 5 The operation of the system is believed to be explainable by the following theory. Considering an anode at the moment a voltage is impressed thereon by the winding 5, the voltage is such that the anode becomes positive with respect to the cathode by the amount of the arc drop. The arc would then be transferred to the anode now under consideration from the anode previously carrying the arc except for the presence of grids. The grid, at 10 that particular instant, carries a negative charge received from the free electrons moving in the tank 8 and, if the grids are made with a sufficiently fine mesh, thereby prevents the anode from receiving the arc. The voltages of the windings 5 and 18 increasing, and being in phase, are in excess of the cathode voltage by a certain amount which is applied to the electrodes of the discharge tube. When such excess voltage reaches the breakdown 15 voltage of the tube, the tube becomes conductive and the excess voltage is applied to the resistance 17 and the grid. The grid 16 acts as an anode and takes the arc while the resistance 17 limits the current flowing to the grid. The blocking action of the grid then 20 immediately ceases and anode 7 takes the arc and carries the load circuit. The penetration voltage of the tube may be reached at an earlier point in the alternating current cycle by increasing the terminal voltage of the winding 18 or battery 22 thereby increasing the average direct current output voltage of the rectifier. The opposite result is, of course, reached by decreasing the terminal voltage of 25 either the winding 18 or the direct current source 22. Such voltage may be adjusted in any desired electrical or mechanical manner and by various well-known means.

Although but two embodiments of the present invention have been illustrated and described, it will be apparent to those skilled in the art that various changes and modifications may be made therein without departing from the spirit of the invention or from the 30 scope of the appended claims.

The invention claimed is:

1. In a system for controlling the operation of an electric current rectifier of the metallic vapor type, a closed tank, anodes extending into said tank, a cathode within said tank, grids arranged adjacent said anodes, an alternating current supply line connected with said anodes, and a discharge tube connected with each of said anodes and with each of said grids.
2. In a system for controlling the operation of an electric current rectifier of the metallic vapor type, a closed tank, anodes extending into said tank, grids arranged adjacent said anodes, an alternating current

supply line connected with said anodes, a discharge tube connected with each of said anodes and with each of said grids, and means for supplying a voltage to said tube in addition to the voltage of said anode.

3. In a system for controlling the operation of an electric current rectifier of the metallic vapor type, a closed tank, anodes extending into said tank, grids arranged adjacent said anodes, an alternating current supply line connected with said anodes, a discharge tube connected with each of said anodes and with each of said grids, means for supplying a voltage to said tube in addition to the voltage of said anode, and means for adjusting the value of the additional voltage supplied to said tube.

4. In a system for controlling the operation of an electric current rectifier of the metallic vapor type, a closed tank, anodes extending into said tank, grids arranged adjacent said anodes, an alternating current supply line connected with said anodes, a discharge tube connected with each of said anodes and grids, the said tubes being supplied with the voltage of said anodes, and an auxiliary transformer connected with and supplying a voltage to each of said tubes and grids in addition to the voltage supplied from said anodes.

5. In a system for controlling the operation of an electric current rectifier of the metallic vapor type, a closed tank, anodes extending into said tank, grids arranged adjacent said anodes, an alternating current supply line connected with said anodes, a discharge tube connected with each of said anodes and grids, the said tubes being supplied with the voltage of said anodes, an auxiliary transformer connected with and supplying a voltage to each of said tubes and grids in addition to the voltage supplied from the associated said anode, and a resistance adjustably connecting each said auxiliary transformer and the associated said grids to vary the voltage impressed thereon.

In testimony whereof I have hereunto subscribed my name this 6th day of August A. D. 1930.

ERNST KOBEL.
